V. L. FORSYTH

SELF ALIGNING PITMAN BEARING BOX

Filed Sept. 21, 1925

Inventor
V. L. FORSYTH

Attorney

UNITED STATES PATENT OFFICE.

VALORIS L. FORSYTH, OF FORT WORTH, TEXAS.

SELF-ALIGNING PITMAN-BEARING BOX.

Application filed September 21, 1925. Serial No. 57,527.

This invention relates to new and useful improvements in self-aligning pitmen bearing boxes.

The object of this invention is to provide certain improvements in the type of box and mounting shown in my Letters Patent No. 1,538,318, issued May 19th, 1925.

A particular object of the invention is to provide means for mounting the box in a web type of pitman as compared with a tubular type.

A further object of the invention is to mount the box on its fulcrum pin so as to be free to shift laterally as well as to rock on said fulcrum pin, thus preventing twisting of the wrist pin and assuring a free and smooth action.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a side elevation of a pitman having a bearing box therein constructed in accordance with my invention,

Fig. 2 is a side elevation of the same, a portion of the pitman being omitted,

Fig. 3 is a vertical sectional view with the stirrup omitted,

Fig. 4 is a cross-sectional view taken on the line 4-4 of Fig. 1,

Fig. 5 is a cross-sectional view taken on the line 5-5 of Fig. 1,

Fig. 6 is a cross-sectional view taken on the line 6-6 of Fig. 2, and

Fig. 7 is a sectional view showing the rib in the box opening of the pitman.

In the drawings the numeral 10 designates a pitman, which as is shown (Fig. 6) is H-shape in cross-section, but which may be made of any of the web shapes commonly used in structural beams. Near the lower end of the pitman a rectangular opening 11 is provided by cutting out the web. A stirrup 12 is suitably attached to the upper end of the web. A bearing box comprising an upper member 13 and a lower member 14 and divided at its transverse center, is mounted in said opening. Each member has a semi-cylindrical seat 15 for receiving a bearing member 16 of suitable metal. The members 16 when assembled provide a cy-

lindrical bore or bearing surface. The details of the foregoing parts may vary according to the conditions of use and manufacture.

In order that the box may rock or oscillate the lower member has a reduced boss 17 disposed transversely of the bore of the bearing members 16. The boss has a longitudinal concaved recess 18 in its under surface, whereby the boss may fulcrum on a pin 19 extending transversely through the pitman and suitably secured therein. Sufficient clearance in the opening 11 around the box is provided so that the box may rock freely. An important feature of the invention resides in the flaring sides 18' given to the recess 18. These sides flare from the center to the outer ends and permit the box to shift or oscillate laterally to either side on the pin, as well as to rock in a vertical plane on said pin.

In preparing the pitman 10, vertical ribs 11' (Figs. 1 and 7) are provided on the side of the opening 11 where the web is cut out. These ribs are rounded off transversely and act to limit shifting of the box longitudinally of the pin 19, thus eliminating end play of the box, but permitting free horizontal and vertical movement as described.

A wrist pin 20 of the usual construction has its collar 21 bearing against the end of the box. For holding the members of the box together a wedge 22 is passed through slots 23 in the pitman parallel to the pin 19. The upper member 13 of the box has a transverse groove 24 provided with a convex bottom cut on a radius having its center co-incident with the center of the pin 19. The under edge of the wedge is curved to conform to the contour of the bottom of the groove.

The wedge is driven in to hold the box and its bearing members in contact with the wrist pin 20 and a cotter pin 25 is passed through one of a series of holes 26 in the wedge to keep the latter in place. It will be seen that the box may rock on the pin 19 because the bottom of the groove 24 will ride under the wedge. This oscillation will be ample to compensate for any variation of the pitman from its perpendicular position with relation to the wrist pin. The flaring recess 18 will compensate any twisting movement by permitting the box to shift horizontally on the pin 19, thus avoiding breaking of the wrist pin or injuring the pitman. It is obvious that the bearing box is adequately supported

and a proper bearing is had for the wrist pin 20. Whenever the pitman is distorted the box will retain its alignment with the wrist pin 20, thus avoiding undue friction, strains 5 and breaks.

Various changes in the size and shape of the different parts, as well as alterations and modifications may be made within the scope of the appended claims. The pitman need 10 not be tubular or flattened, but may be otherwise constructed to receive the box.

What I claim, is:

1. The combination with a pitman, of a fulcrum pin mounted therein, a wrist pin bearing box having a concave rocking seat upon its under face for circumferential movement upon said pin and the sides of said seat being flared from its center outwardly to form a bearing point to permit 15 said box to oscillate transversely to the axis of said pin, and means for holding the box in the pitman against vertical movement relative to the fulcrum pin but permitting rocking movement thereon.
2. The combination with a pitman, of a fulcrum pin mounted therein, a wrist pin bearing box having a concave seat upon its under side for circumferential rocking upon said pin and the sides of said seat being 20 flared in opposite directions to form a central bearing to permit said box to oscillate transversely to the axis of said pin, and a fastening device in the pitman with which the upper portion of the box has rocking engagement.
3. The combination with a pitman having an opening and vertical ribs on each side thereof, of a wrist pin bearing box mounted in the opening of the pitman and having its 25 ends terminating at the ribs thereof, a boss upon the lower portion of the box having a lengthwise bearing at a right angle to the bore of the box and a flared side wall having a bearing at substantially the longitudinal 30 center of the bore to permit said box to oscillate transversely of its lengthwise bearing, a transverse fulcrum pin in the pitman engaging the lengthwise and side wall bearings of the boss to permit oscillation upon 35 either bearing, and means for retaining the

bearing box in engagement with said fulcrum pin.

4. The combination with a pitman having an opening, of a wrist pin bearing box mounted in the opening of the pitman, a boss 45 on the lower portion of the box having a lengthwise bearing at right angles to the bore of the box and provided with a transverse pivot intermediate the ends of said bearing, a transverse fulcrum pin in the pitman mounted to oscillate in said bearing or upon said pivot of the box, the upper portion of the box having a groove with a convex bottom, and a fastening member mounted in the pitman and engaging in said 55 groove, the groove having a width greater than the thickness of the fastening device to allow the box to rock.

5. The combination with a pitman, of a wrist pin bearing box having a rocking seat 60 in its under side, a fulcrum pin mounted in the pitman and engaged in the seat of the box, said seat being formed to permit the box to rock circumferentially upon the pin and to oscillate transversely to the axis of the 65 pin by a pivot thereon, means for holding the box in contact with the pin, and means engaging the sides of the box for preventing movement of the box axially of the pin while permitting the circumferential and 70 transverse movements of the box.

6. The combination with a pitman having an opening and vertical ribs on each side of the opening, of a wrist pin bearing box mounted in the opening of the pitman, having its ends terminating at the ribs of the pitman opening, a boss on the lower portion of the box having a flared recess at right angles to the bore of the box, a transverse 75 fulcrum pin in the pitman engaged in the 80 recess of the box, the upper portion of the box having a groove with a convex bottom, and a fastening member mounted in the pitman and engaging in said groove, the groove having a width greater than the thickness 85 of the fastening device to allow the box to 90 rock.

In testimony whereof I affix my signature.

VALORIS L. FORSYTH.
